UNITED STATES PATENT OFFICE.

FEDERICO WERTH, OF MILAN, ITALY.

APPARATUS FOR GALVANIZING METAL TUBES, RODS, &c.

970,149.

Specification of Letters Patent. Patented Sept. 13, 1910.

Application filed December 11, 1909. Serial No. 532,634.

To all whom it may concern:

Be it known that I, FEDERICO WERTH, a citizen of the Kingdom of Italy, residing at No. 18 Corso Vercelli, Milan, Italy, have invented a new and useful Improvement in and Relating to Apparatus for Galvanizing Metal Tubes, Rods, and the Like; and I do hereby declare the following to be a full, clear, and exact description of the same.

10 The present invention has for its object an apparatus for galvanizing metal tubes, rods and the like, either on the surface alone or both on the inside and outside of tubes. The apparatus of this kind heretofore employed 15 comprises, broadly speaking, a mechanism arranged upon a rotatable shaft and always immersed in the electrolyte. With this arrangement it is only possible to operate with anodes which are arranged on the sides of 20 the vessel containing the electrolyte; with this method it is also only possible to arrange circular disks or drums on the rotary shaft and the size of the diameter of the disks can be but small for practical purposes, so that only a small number of tubes 25 can be exposed in the bath, because the defects of such apparatus increase with the increase of diameter.

The present invention has for its object to 30 introduce improvements into apparatus of the kind referred to, by means of which the time during which the material to be treated has to be exposed to the galvanic bath is reduced, thereby diminishing the working expenses.

The accompanying drawing illustrates a constructional form of the apparatus embodying the present invention.

Figure 1 is a vertical section, Fig. 2 is a 40 sectional plan view, and Fig. 3 is an end elevation.

45 *a* (Fig. 2) is the driving shaft of the apparatus which is operated by a belt pulley or a gear wheel *b*. Gear wheels *c*, *c'*, *c''* are mounted on the shaft *a*, being secured to the shaft at suitable intervals one from the other in such a manner that they can be displaced longitudinally and fixed on the shaft.

50 Parallel with the driving shaft *a* a second shaft *d* is arranged on which three gear wheels *e*, *e'*, *e''* are displaceably mounted in a similar manner to the gear wheels on the shaft *a* with 55 which they correspond in size; the gear wheels on the two shafts are adapted to be

engaged in accordance with various requirements. The two shafts *a* and *d* are carried in bearings *f* fixed on U shaped irons. These U irons are arranged parallel one with the other in the longitudinal direction over the vessel *A* containing the electrolyte.

Additional bearings *g*, *g'*, *g''* (Fig. 1) are preferably arranged at the lower part of the two U irons immersed in the bath. Gear wheels *h*, *h'*, *h''* or the like are rotatably mounted in these bearings, their planes of rotation corresponding with those of the wheels *c* and *e*. These systems of wheels are adapted to rotate endless chains *i*, *i'*, *i''* of any suitable kind, bands, or their equivalents, in a plane which is perpendicular to the surface of the electrolytic bath. The chain *i* which corresponds to the system of wheels *c*, *e*, *h* carries on its links, at appropriate intervals one from the other, a number of clamping devices *l*, *l'*, *l''* and so forth directed in accordance with the plane of movement of the other chains and serving for clamping the inner anodes. The other two chains *i'*, *i''* which correspond to the two other systems of wheels, carry on their links annular suspension devices *m*, *m'*, *m''*, *m'''* and so on and *n*, *n'*, *n''*, *n'''* and so on, corresponding in number and position to the clamping devices *l*; the direction of these suspension devices likewise coincides with the plane of movement of the corresponding chains.

The tubes or rods that are to be galvanized are introduced into two corresponding rings *m* and *n* on the two chains *i'*, *i''* by which they are conveyed during the galvanizing process.

The inner anodes *p* are fixed to the clamping devices *l* and are inserted in the known manner in the form of thin metal rods in the interior of the tubes and serve for galvanizing the inner surface of the tubes.

As already stated above, the chains can be shifted relatively to each other along the driving shaft and similarly the bearings for the shafts and the lower wheels with the suspension bearings are displaceable in the longitudinal direction, so that the shaft bearings and gear wheels, chains or the like wheels and chains constitute a group which is displaceable integrally. The object of this

arrangement is to enable the same apparatus to be used for any normal length of tube or rod. With tubes of great length it is advantageous to provide another group of chains 5 at the other end of the shaft in order to facilitate the operation and the supply of current to the inner anodes.

The outer anodes —*o*— can be arranged not only on the side walls of the vessel 10 —*A*— as shown in Figs. 2 and 3 but can also be arranged inside the paths of the chains so that the articles to be galvanized carried by the chains are always located between two rows of anodes and in as close proximity 15 thereto as possible both during their upward and downward travel. Obviously, when this appears to be desirable, two rows of anodes instead of one can be arranged in the interval between the chains in such a 20 manner that the material to be galvanized is always situated between a pair of anodes both on the admission and on the delivery side and as close thereto as possible.

The advantages of the arrangement in accordance with the present invention are as 25 follows: In the first place the driving shafts are located entirely outside the electrolyte so that these very important parts of the apparatus are never exposed to the harmful influence of the electrolytic bath. Then the 30 arrangement of the suspension devices for the material to be galvanized, which are preferably constructed as rings fixed to an endless chain, enable the bath to receive a 35 greater charge and also render it possible to increase the charge as desired merely by adding new links provided with rings as only the depth of the vessel —*A*— need be increased, which does not present any difficulty either in the case of wood or cement tanks. Owing to the possibility of enlarging 40 the plant in this simple manner important advantages are obtained: 1. An economy of space, because increasing the depth of the tank presents no difficulties while any increase in the size of a disk apparatus necessitates lateral extension and consequently complete alterations of the tank and chamber. 2. An important increase in the output 45 of the plant without the necessity for more space so that any installation can be run for years with the same plant. 3. The larger the plant the more convenient the operation, as the installation of the baths remains the same, the only difference being that more workmen are required.

As the material to be galvanized must necessarily run for a certain time between two 50 parallel outer rows of anodes and as further, owing to the form of the suspension devices, the said articles also rotate continuously about themselves, during the vertical part 55 of the path all the surfaces of the material to be galvanized are uniformly subjected to the action of the anodes so that the galva-

nizing proceeds uniformly and perfectly in every way. In the case of large apparatus the tubes can likewise be given a continuous movement of rotation the inner surface of the rings being made rotatable and provided with gear wheels which during the vertical movement strike on tappets arranged laterally on the guides of the lower wheels. 70

As already stated above the arrangement of the chains for both electrodes is similar. 75 The inner anodes —*p*— which consists of thin metal rods arranged inside the tubes to be galvanized and fixed to the clamping devices —*l*— of the chain —*i*— are always held at the proper height during the operation. Any usual commercial length of tube or rod requires only three chains with this arrangement, two of them (the chains —*i'*— and —*i''*—) carrying the suspension means 80 for the material to be galvanized. For specially long tubes an anode guide can be arranged at each end of the apparatus. It is therefore sufficient to displace the devices arranged on the *U* irons and driving the chains, in the longitudinal direction so that 85 the same apparatus may be used for any length of tube or rod. 90

Another advantage obtained by means of this apparatus is that owing to the arrangement of the driving shaft at an adequate 95 height above the level of the bath during the slow movement of the apparatus a part of the suspended material to be galvanized alternately leaves the bath completely. This procedure proceeds for a sufficient length of 100 time to enable the process of galvanizing to be supervised and the finished tubes to be removed and replaced by fresh ones.

The various constituent parts of the apparatus are constructed in the following manner: The annular suspension devices —*m*— and —*n*—, which constitute projections from the chain links, or which can be attached thereto in any convenient manner, may advantageously be made of an internal 105 diameter of say 10 centimeters so that the apparatus can be employed for any size of tube and rod up to this diameter. In the case of tubes or rods of smaller diameter, two or more of them may advantageously 110 be assembled loosely and carried by a single pair of rings. When tubes are to be galvanized which present a larger diameter than 10 cm. the apparatus can be furnished with rings of correspondingly larger diameter 115 which can readily be substituted for the normal rings. The metal parts immersed in the electrolyte are preferably protected by a suitable insulating substance. In applying 120 this protecting substance of course those parts are omitted which must necessarily constitute the contacts for the production of the galvanizing process. Thus for example the inner edges of the suspension devices for 125 the articles to be galvanized and also the 130

contact faces and contact points between the chain links and the teeth of the wheels should not be insulated. The lower wheels entering the bath may advantageously consist of non-conducting material so that useless deposits and loss of current are prevented. The driving shaft —a— is connected with the negative pole of the circuit. The gear wheels —c'— and —c''— which drive the chains with the suspension means for the material to be galvanized, are fixed to the said shaft without any insulation, while the wheel —c— which serves for driving the chain carrying the suspensions for the inner anodes, is fixed in a well-insulated manner upon the said driving shaft —a—. This wheel is connected with the positive pole of the circuit. The rods which constitute the anodes for internal galvanizing should likewise be insulated in a suitable known manner. The middle and the lateral anodes are likewise insulated the former suspended in the U irons and the latter on the copper conductors which are insulated from the side walls of the vessel. These anodes should be connected up with the positive pole of the circuit. The chain which presents the suspensions for the internal anodes is also preferably suitably insulated from the action of the bath only the points forming the contact being left free. This chain

may, however, also be formed of conducting material such as aluminium for example which should not be soluble in the bath.

Having now particularly described and ascertained the nature of my said invention and in what manner the same is to be performed, I declare that what I claim is:—

1. In an electroplating apparatus, the combination of an electrolytic vat, a driving shaft, an endless carrier operated by the driving shaft, and rings attached to the endless carrier and supporting the objects to be electroplated.

2. In an electroplating apparatus, a vat, a driving shaft, a pair of gear wheels carried by the driving shaft, a pair of endless chains actuated by the gear wheels, rings attached to said chains, hollow tubes supported in said rings, anodes lying within the hollow tubes, in combination with an auxiliary chain actuated by the driven shaft and carrying the inner anodes at the same rate of speed as the hollow tubes.

In testimony whereof, I have signed my name to this specification in the presence of two subscribing witnesses.

FEDERICO WERTH.
